DANY D. CANFIELD, OF NASHVILLE, TENNESSEE.

FEEDING DEVICE FOR FLAT-WORK IRONERS.

1,406,823.

Specification of Letters Patent. Patented Feb. 14, 1922.

Application filed September 27, 1919. Serial No. 326,923.

To all whom it may concern:

Be it known that I, DANY D. CANFIELD, a citizen of the United States, residing at Nashville, in the county of Davidson and State of Tennessee, have invented certain new and useful Improvements in Feeding Devices for Flat-Work Ironers, of which the following is a specification.

This invention relates to feeding devices for flat work ironing machines.

The object of the invention is to facilitate shifting of the loaded and unloaded conveying tables or bars to and from the feeding position in a manner to do away with the necessity of lifting and carrying them back and forth, as in prior devices for this purpose.

Further objects of the invention are in part obvious and in part will appear more in detail hereinafter.

The invention comprises the construction and arrangement of parts hereinafter described and claimed.

In the drawings, Fig. 1 is a perspective view of one form of feeding device embodying the invention; Fig. 2 is a front elevation thereof, as viewed from the direction of the ironing machine to which the work is to be fed; Fig. 3 is a bottom plan view of the track. Fig. 4 is a side elevation; Fig. 5 is in part an elevation and in part a sectional elevation on the line 5—5, Fig. 4, of one end of the device; Fig. 6 is a similar view showing the table supported in unloaded position; Fig. 7 is a sectional plan view on the line 7—7, Fig. 5; Fig. 8 is a sectional elevation on the line 8—8, Fig. 5; and Fig. 9 is an elevation, illustrating an adjustment of the support.

Briefly described the apparatus of the present invention embodies a suitable frame carrying an endless track, a hanger riding and guided in said track, and a conveyor table or bar supported by the hanger. Usually a plurality of conveyor tables are thus mounted upon the track, the arrangement being such that the several conveyor tables can be shifted back and forth between the loading and unloading stations without interfering with each other.

In the specific embodiment shown in the drawings, 1 indicates several supporting posts, four of which are shown, which rest upon the floor or other suitable support at

the entrance to the flat work ironer, the first roll or work receiving member of which is indicated at 2, Fig. 4. The flat work ironer may be of any suitable form or construction and no further description thereof is necessary.

Posts 1 are preferably connected to provide a rigid frame structure with definite spacing of the parts. For this purpose each post has slidably mounted thereon a sleeve joint member 3, the several sleeve members 65 being connected by longitudinal bars 4 and transverse bars 5. This forms a rectangular upper frame which can be raised or lowered to meet special conditions and may be secured in any adjusted position by introducing bolts or pins 6 through openings 6^a in the members 3 and into the proper ones of a series of vertically spaced openings 7 in the posts 1. This adjustment is made to secure the proper horizontal relation between the 75 loaded conveyor table and the ironing machine to which the work is fed, or to suit the convenience of the operator of the device.

Each of the longitudinal rods 4 serves as a 80 support for an endless track 8, being held thereto by clamps 9 embracing the bars 4 and connected to the tracks by bolts 10. This track is of endless form, as shown in Fig. 3, and includes inner and outer members 11, 85 12 connected at intervals by cross bars 13, said members 11, 12 having bottom flanges or shoulders 14 to support the traveling rollers, as will appear. 15 indicates one of a plurality, three being shown, of conveyor 90 tables or bars upon which the work to be ironed, such as shirts, table cloths, pillow cases, or other flat work is placed, as shown at 15^a, Fig. 4. The form of these bars or tables is immaterial, the invention having to do solely with the means and manner of supporting the same and permitting movement thereof to the different required positions in handling the work. Each conveyor table is in the form of a long bar supported or carried at both ends by rollers which travel along the tracks 11. The supports for both ends of the bar are identical, each traveling in its own set of tracks. In other words, the construction is duplicated at both ends of the 100 device so that description of one end of the device will suffice for both.

As illustrated, each table 15 at its end is

provided with a sleeve 16 having an ear 17 pivotally connected to a clevis 18 on the lower end of a rod 19 provided with a collar 20 rigidly secured thereto in any suitable manner, such as by the cross pin 21. Said rod extends through a cap 22 threaded upon the lower end of a pipe 23 having a clevis 24 secured to a link 25 supported by the axle of a pair of rollers 26 traveling 10 along the flanges 14 of the track. Bar 19 within the pipe 23 is provided with a larger stop portion 27, which rests upon the cap 22 and serves as a support for the pendant table 15. The member 27, however, may be 15 raised in the pipe 23 to permit the table to be elevated, as will appear. This construction also permits swivel motion between the bar 19 and pipe 23. On the cap 22 is pivoted a U-shaped locking member 28 having a notch or recess 29.

Table 15 at its end is provided with a longitudinal cavity or recess in which is a compression spring 30 tending to force outwardly a ball 31, which projects from the 25 opening in the end of the sleeve 16. The purpose of this ball is to interlock with a groove or channel 32 lying substantially vertical but preferably at a slight incline, as shown in Fig. 8, said groove being in the 30 wall of a sleeve-like support 33 suitably clamped, such as by the set screw 34, in any adjusted position on the forward posts 1 of the frame. Said supports are provided with cavities 35 having stop shoulders 36, inclined floors 37, beveled at their front edges 38, and a side wall 39 having a beveled portion 40 and in which is the vertical channel 32 before referred to.

The operation is as follows:

40 Fig. 4 represents three conveyor tables supported by the frame, one in each of the several positions assumed by said tables. A indicates the unloading position; B indicates the unloaded position; and C indicates the 45 loading position. At the unloading position the conveyor table is supported by its rod and pipe connections to the track rollers, said connections lying inclined, as shown. The stop members 27 rest directly upon the 50 caps 22. Sleeves 16 have been swung forwardly into position in the cavities of the supports 33 and the balls 31 have yielding engagement with the channels 32 and hold the conveyor table in the position shown. Two operators deliver the work from the conveyor table in position A to the ironing machine, one of said operators being located at each end of the table. When the 55 table is unloaded the two operators grasp the ends of the table and elevate it, at the same time manipulating the catches 29 so as to engage the same beneath the collars 20, as shown in Fig. 6. This operation leaves the unloaded conveyor table at a higher elevation and the operators immediately push 60

it back to position B, the rollers traveling along the inner portions of the tracks until the table reaches approximately position B.

While the feeding operators have been unloading the conveyor table at position A, 70 two other operators, called loaders, have been loading the conveyor table hanging at the loading station C. These operators, after loading the table, push it forwardly or to the right in Fig. 4, by moving the rollers along the outer portions of the tracks, as shown in dotted lines, Fig. 2. In this position, with the rollers in the outer portions of the tracks the links or rods from which the loaded table is suspended lie outside and 75 will pass around the links or rods of the unloaded conveying table being moved backwardly along the inner portions of the tracks. When the loaded table has been advanced the feeders pull it forward and lock 80 it in the loading position A and again begin to feed the ironing machine, as before stated. The loaders pull back the unloaded table at position B, unhook the latches 29 and drop the table itself to the lower loading level at station C and proceed to load the table. During operation of the device, looking down upon it from above, the rollers travel in a counterclockwise direction along the nearer track, Fig. 1, and in a clockwise 85 direction along the distant track.

With this arrangement two operators are always feeding the ironing machine and two operators are loading another table, so that the ironing machine is constantly kept in 100 operation.

What I claim is:—

1. Feeding mechanism for ironing machines, comprising a guide having portions extending toward and away from a working 105 position, and a plurality of horizontal work supporting bars, each movable along both of said guiding portions, said bars being also adjustable vertically toward and from said guide to pass over and under each 110 other while moving along the same.

2. Feeding mechanism for ironing machines, comprising a guide having two substantially horizontal portions extending toward and away from a working position, 115 a plurality of horizontal work supporting bars extending transversely to said guiding portions and each movable along both thereof, said guiding portions being horizontally spaced from each other and said bars being 120 vertically adjustable relative thereto, whereby two work supports moving in opposite directions will pass over and under each other without interference.

3. Feeding mechanism for ironing machines, comprising two guides each of which has two guiding portions extending toward and away from a working position, a horizontally extending work support having two carrying members one traveling along each 125 130

of said guides, said members being arranged to travel along the inner guiding portions when moving in one direction and along the outer guiding portions when moving in the other direction.

4. Feeding mechanism for ironing machines, comprising two guides each of which has two guiding portions extending toward and away from a working position, a horizontally extending work support having two carrying members one traveling along each of said guides, said members being arranged to travel along the inner guiding portions when moving in one direction and along the outer guiding portions when moving in the other direction, and means for adjusting said work supports relative to said carrying members.

5. Feeding mechanism for ironing machines, comprising two guides each of which has two guiding portions extending toward and away from a working position, a work support having two carrying members one traveling along each of said guides, said members being arranged to travel along the inner guiding portions when moving in one direction and along the outer guiding portion when moving in the other direction, and means for locking said work supports stationary in said working position.

6. Feeding mechanism for ironing machines, comprising two guides each of which has two guiding portions extending toward and away from a working position, a horizontally extending work support having two carrying members one traveling along each of said guides, said members being arranged to travel along the inner guiding portions when moving in one direction and in the outer guiding portions when moving in the other direction, means for adjusting said work support relative to said carrying members, and means for locking said work support stationary in said working position.

45 7. Feeding mechanism for ironing machines, comprising two guides each of which has two guiding portions extending toward and away from a working position, a plurality of horizontally extending work supports each having two carrying members one traveling along each of said guides, said members being arranged to travel along the inner guiding portions when moving in one direction and along the outer guiding portions when moving in the other direction, said work supports being adjustable vertically to either of two positions, and means for holding the same in either of said positions while moving along said guides.

60 8. Feeding mechanism for ironing machines, comprising two endless guides, and a plurality of work supports each having supporting members traveling along both of said guides.

65 9. Feeding mechanism for ironing ma-

chines, comprising two endless guides lying in substantially the same horizontal plane, and a plurality of horizontally extending work supports having supporting members traveling along both of said guides.

10. Feeding mechanism for ironing machines, comprising two endless guides, and a plurality of work supports each having supporting members traveling along both of said guides, the movement of the supporting members along one guide being in a clockwise direction and along the other guide in a counter clockwise direction.

11. Feeding mechanism for ironing machines, comprising two endless guides lying in substantially the same horizontal plane, and a plurality of work supports having supporting members traveling along both of said guides, the movement of the supporting members along one guide being in a clockwise direction and along the other guide in a counter clockwise direction.

12. Feeding mechanism for ironing machines, comprising two endless guides, and a plurality of work supports each having supporting members traveling along both of said guides, said work supports being adjustable toward and from said supporting members to pass each other while traveling along said guides.

13. Feeding mechanism for ironing machines, comprising two endless guides lying in substantially the same horizontal plane, and a plurality of work supports having supporting members traveling along both of said guides, said work supports being adjustable toward and from said supporting members to pass over and under each other while traveling along said guides.

14. Feeding mechanism for ironing machines, comprising two endless guides, and a plurality of work supports each having supporting members traveling along both of said guides, the movement of the supporting members along one guide being in a clockwise direction and along the other guide in a counter clockwise direction, said work supports being adjustable toward and from said supporting members to pass each other while traveling along said guides.

15. Feeding mechanism for ironing machines, comprising two endless guides lying in substantially the same plane, and a plurality of work supports having supporting members traveling along both of said guides, the movement of the supporting members along one guide being in a clockwise direction and along the other guide in a counter clockwise direction, said work supports being adjustable toward and from said supporting members to pass each other while traveling along said guides.

In testimony whereof I affix my signature.

DANY D. CANFIELD.

Certificate of Correction.

It is hereby certified that in Letters Patent No. 1,406,823, granted February 14, 1922, upon the application of Dany D. Canfield, of Nashville, Tennessee, for an improvement in "Feeding Devices for Flat-Work Ironers," errors appear in the printed specification requiring correction as follows: Page 1, line 71, after the reference numeral "6^a," for the letter "n" read *in*; page 2, line 122, claim 2, strike out the words "work support" and insert the word *bars*; and that the said Letters Patent should be read with these corrections therein that the same may conform to the record of the case in the Patent Office.

Signed and sealed this 17th day of April, A. D., 1922.

[SEAL.]

KARL FENNING,
Acting Commissioner of Patents.
